UNITED STATES PATENT OFFICE.

EARL R. GRIBBEN, OF POLK, OHIO.

TILL.

1,261,515.

Specification of Letters Patent.

Patented Apr. 2, 1918.

Application filed May 31, 1916. Serial No. 100,861.

To all whom it may concern:

Be it known that I, EARL R. GRIBBEN, a citizen of the United States, residing at Polk, in the county of Ashland and State 5 of Ohio, have invented new and useful Improvements in Tills, of which the following is a specification.

This invention relates to a till which may be connected with a counter or advantage- 10 geously used in connection with a cash register.

The primary object of the invention is to provide a till having a section forming a bottom and end wall thereof with the section 15 recessed to provide the same with a face curved upwardly and inwardly at one end of the section upon the arcs of two circles with a portion of the curved surface formed by one of the arcs providing a transversely 20 extending lip to cause change while being removed from the till to be directed into the hand of the person removing the change.

Another object of the invention is to curve the upper face of the section which forms 25 an end and bottom of the till in such a manner that as the change is moved over the curved face of said section, it will be directed toward the rear of the till when brought into contact with the lip formed 30 by the curved face of said section thus obviating the likelihood of the change being spilled upon the floor while being withdrawn from the till.

A further object of the invention is to 35 provide the section with a face curved in such a manner that when the thumb of the person withdrawing the change from the till is rested upon the lip and the money engaged with the forefinger and moved up- 40 wardly over said curved face, it will be brought into contact with the ball of the thumb thus facilitating the removal of change from within the till.

A still further object of the invention is 45 to provide sides for the till which are recessed for a portion of their length on their upper edges to co-act with the overhanging lip on said section in facilitating the removal of change from the till.

With these and other objects in view, the 50 invention resides in the novel combination and arrangement of parts which will be hereinafter described and particularly pointed out in the claim.

The preferred embodiment of the invention 55 has been illustrated in the accompany-

ing drawing, although no restriction is necessarily made to the precise details of construction therein shown, as changes, alterations, and modifications within the scope 60 of the claim may be resorted to when desired.

Like characters of reference denote corresponding parts through the several views in the drawing, in which:

Figure 1 is a perspective view looking at the front end of the till constructed in accordance with the invention.

Fig. 2 is a perspective view of the till looking at the rear end thereof.

Fig. 3 is a vertical longitudinal sectional view through the till.

Referring now to the drawing in detail, the numeral 1 designates a section of the till which is recessed, as at 2, to form a face 3 75 curved upwardly and inwardly at one end of the section upon the arc of two circles with the radius of one of the arcs being approximately one-fourth the length of the radius of the other arc to provide a lip 4. The 80 lip 4 extends inwardly of the till to overhang the curved face 3 and extends transversely of the section 1.

The recess in the section 1 enables the same to serve as an end wall and a bottom for 85 the till, while the lip 4 is so arranged as to provide a thumb rest upon which the thumb may be placed when withdrawing money from the till. Side walls 5 are secured to the sides of the section 1 and each side wall 90 is recessed for a portion of its length along its upper edge, as at 6, said recess extending from the lip 4 to the rear end of the section 1, so that the upper edge of the side walls are spaced slightly below the lip 4 in the 95 rear thereof to enable money to be more easily withdrawn from the till than would be possible if the upper edge of the side walls 5 were to lie in the same plane as the lip 4.

An end wall 7 is secured to the side walls 5 and to the reduced end of the section 1, thus completing the till.

In removing change from the till, the thumb is placed on the lip 4 and the fingers 105 are inserted within the till and placed upon the change therein. By moving the fingers toward the thumb, the change is moved over the curved face on the section 1 and directed by the lip 4 toward the end wall 7 and 110 upon the fingers, so that should the change slide therefrom it will fall upon the portion

of the curved face 3 formed by the circle having the longer radius and directed by this portion of the curved surface toward the end wall 7 of the till.

5 When a single piece of money is to be removed from the till, it will be seen that as the money is moved upwardly over the curved face 3, the lip 4 directs the coin between the ball of the thumb and the finger 10 engaged with the coin, so that there is no unnecessary movement of the thumb or finger required to firmly grip the coin when the same has been passed beyond the lip 4 as is the case with money tills now in common 15 use.

From the foregoing description, taken in connection with the accompanying drawing, it is at once apparent that a till has been provided which although simple in construction and inexpensive of manufacture is so

constructed as to prevent change from being spilled while being removed therefrom.

Having thus described the invention, what is claimed as new, is:

A coin till including a rectangular box-like structure, the front and bottom whereof being formed from a single element, the bottom being gradually inclined upwardly from the back of the till to the front thereof and being further rounded upwardly to the said front, the front, upon its inner face being concaved from the said rounded portion of the bottom and being arranged at an outward angle from the terminal of the rounded concaved portion providing the inner 35 edge of the front with a pointed lip the top of the front being straight and being elevated above the sides of the till.

In testimony whereof I affix my signature.
EARL R. GRIBBEN.
